(57) **CLAIM**

I claim the ornamental design for a razor handle, as shown and described.

DESCRIPTION

FIG. 1 is a perspective view of the razor handle of the present invention.

FIG. 2 is a top plan view of the razor handle of the present invention.

FIG. 3 is a bottom plan view of the razor handle of the present invention.

FIG. 4 is a right side elevation view of the razor handle of the present invention.

FIG. 5 is a left side elevation view of the razor handle of the present invention.

FIG. 6 is a front elevation view of the razor handle of the present invention; and,

FIG. 7 is a rear elevation view of the razor handle of the present invention.

The broken lines illustrate portions of the razor handle and form no part of the claimed design.
